UNITED STATES PATENT OFFICE.

ELIE FORMAN, OF BOSTON, MASSACHUSETTS.

CAP.

1,049,838.

Specification of Letters Patent.

Patented Jan. 7, 1913.

Application filed April 17, 1912. Serial No. 691,453.

To all whom it may concern:

Be it known that I, ELIE FORMAN, a citizen of the United States, residing at Boston, county of Suffolk, State of Massachusetts, have invented an Improvement in Caps, of which the following description, in connection with the accompanying drawing, is a specification, like characters on the drawing representing like parts.

10 This invention has for its object to provide a novel cap frame which is light and yet elastic.

The invention is particularly adapted for caps of the type which conductors, motor-men, or other uniformed persons commonly wear, as it will keep its shape under all circumstances and is light and, therefore, comfortable to wear.

15 The invention relates particularly to the manner in which the frame for the cap is made and comprises the features which will be more fully hereinafter described and then pointed out in the appended claim.

20 Referring to the drawings wherein I have illustrated one embodiment of my invention, Figure 1 is a vertical longitudinal section through a cap embodying my invention; Fig. 2 shows a portion of the blank from which the frame is made; Fig. 3 is a perspective view of the frame.

25 The cap herein illustrated is of the bell crown flat-topped variety, although my invention is not limited to use in a cap of this particular type.

30 The frame herein shown is designated generally by 1 and it supports and holds in shape the outer covering 2 of cloth. The lower edge of the outer covering 2 is folded under the lower edge of the frame, as at 3, and is sewed to the lower edge of the frame.

35 4 designates the usual sweat band which is sewed at its lower edge to the outer covering 2, as at 5. 6 is the usual vizor held in place in the usual way by stitches 7.

40 45 These parts, with the exception of the frame, may have any suitable or usual construction and form no part of the present invention.

The frame 1 is made of resilient material so that it will always resume its proper shape even after it has been bent out of shape, and it is also made of light material so as to make a light weight cap. The frame is made of strips of material woven together so as to make the construction hereinafter referred to. The strips may be of any material which has the desired char-

acteristics, but I prefer to use the cane material that is ordinarily used in forming the cane seats of chairs. The blank from which the frame is made is shown in Fig. 2 and is 60 in the form of a strip of material having a length equal to the circumference of the cap and a width equal to the height of the frame. This blank is formed of longitudinal strips 8 and cross strips 9 which are interwoven 65 together in ordinary fashion in a manner similar to that in which the seats of cane chairs are woven together. As shown in the drawings, these strips 8 and 9 are woven together after the manner of a plain weave. 70 The cross strips 9 extend at one edge beyond the longitudinal strips 8, as shown at 10. A blank of this sort can be made by simply taking a strip of woven cane material of the desired length and width and 75 then removing the longitudinal strands at one edge of the strip to provide the projecting portions 10 of the cross strands. The blank thus made is formed into circular shape by bringing the ends 11 and 12 thereof 80 together and fastening them to each other in any suitable way, either by stitches or by a binding tape. The edge 13 is bound with tape 14, said tape being sewed to the edge by stitches 15 and thus protecting the 85 edge and preventing it from ravelling. Similarly, the edge 19 is bound by a tape 16 which is sewed to the strands 9, and in order to get the bell crown shape the extremities of the ends 10 of the cross strips 9 are separated slightly from each other so that said 90 projecting ends 10 have a slightly divergent arrangement. I prefer to use a wire at the flared edge 19, said wire 20 being covered by and sewed into the tape 16, and preferably being located on the inside of the strands 9 and thereby giving strength to the upper edge of the frame and holding it in its divergent shape, as seen in Fig. 3. If desired, the body of the crown may be further reinforced by a reinforcing wire 17 which is taped thereto, although this is not essential. The frame thus made is put into the cap in usual way and the cover and sweat band sewed in place. The cane material is 105 very resilient and will resume its proper shape even after it has been distorted by a blow or otherwise. Caps of this nature are often subjected to blows, and if the frame is not resilient any pressure or blow on the 110 cap will tend to distort the frame and destroy the shape of the cap. By using this

resilient material, however, the cap will always preserve its proper shape. Moreover, the cane material is exceedingly light, and as a result a light hat can be made which 5 is a great advantage as many hats of this nature are rather heavy.

One advantage of my construction is that the frame is practically unbroken around the circumference of the cap; and, therefore, 10 the cloth cover of the cap is supported at all points on the sides. The circular shape of the cap is thereby preserved in a much better way than would be possible where the cloth at the sides of the cap is supported at intervals only. Another advantage of the cane 15 material is that it does not lose its elasticity by becoming damp or moist.

While I prefer to use ordinary cane material for the frame because it is resilient as 20 well as light, yet my invention is not necessarily limited to the use of this material.

Having fully described my invention,

what I claim as new and desire to secure by Letters Patent is:—

In a bell crown cap, the combination with 25 a cap frame made of strands of resilient material woven together and arranged with one set of strands extending vertically from top to bottom of the frame and the other set extending annularly of said frame at its 30 lower side only, the upper end of the vertical strands extending above the annular strands and having a divergent relation at their upper ends, of a binding tape secured to the upper ends of said vertical strands 35 and holding them in their divergent position, and a covering inclosing said frame.

In testimony whereof, I have signed my name to this specification, in the presence of two subscribing witnesses.

ELIE FORMAN.
